(57) **CLAIM**

The ornamental design for a combined voter terminal storage and transport cart, as shown and described.

DESCRIPTION

FIG. 1 is a front perspective view of a voter cart according to our new design with the front doors closed.

FIG. 2 is a left mirror-image view of the voter cart as in FIG. 1;

FIG. 3 is a front perspective view of the voter cart as in FIGS. 1-2 with the front doors opened.

FIG. 4 is a top perspective view of the voter cart as in FIGS. 1-3 with front doors and top lid opened.

FIG. 5 is a back perspective view of the voter cart as in FIGS. 1-4 with back doors opened.

FIG. 6 is a back perspective view of the voter cart as in FIGS. 1-5 with the back doors closed; and,

FIG. 7 is a top view of the voter cart as in FIGS. 1-6 with the front and back doors closed.
